[57] CLAIM

The ornamental design for an electrotransport drug delivery patch, as shown.

DESCRIPTION

FIG. 1 is a top perspective view of an electrotransport drug delivery patch, showing our new design;
FIG. 2 is a top plan view thereof;
FIG. 3 is a bottom plan view thereof;
FIG. 4 is a side elevational view thereof, the opposite side elevational view being identical thereto; and,
FIG. 5 is an end elevational view thereof, the opposite and elevational view being identical thereto.
